BOBBY PIN PACKAGE

Wythe T. Bolling, Jr., Scranton, Pa.

Application April 22, 1946; Serial No. 664,039

4 Claims. (Cl. 206—66)

1

The present invention relates to improvements in containers and more particularly to a package in which bobby or other hair pins may conveniently be nested.

One of the objects thereof is to provide a simple, efficient and inexpensive package for bobby pins and the like which is characterized by the fact that it snugly receives, holds, makes instantly accessible, and completely encloses a row of bobby or hair pins in a one-piece container.

Another object thereof is to provide a package for nesting bobby and other types of hair pins, which is made from parts or panels folded out from a single blank of material in such a manner and shape that a row of hair pins may conveniently be sandwiched between a backing and a cover panel thereof.

A further object thereof is to provide a package for nesting hair pins and similar notions in which is employed a novel principle of construction. In accordance with this principle of construction, a pair of oppositely arranged guards are mounted marginally of the stand upon which the hair pins are suspendingly nested in straddling relation, which guards present fluted marginal portions against the wire shanks of the several hair pins to prevent the hair pins working off endwise of the stand, and becoming displaced therefrom.

A still further object thereof is to provide a package for bobby and other hair pins which is provided with integral means for nesting them in exposed as well as accessible disposition.

Another object thereof is to provide a package or container for hair pins in which use is made of integral means for nesting them in single row for removal purposes, in abutting relation, and with only their opposing ends engaged for holding purposes.

With the above and other objects in view, my invention consists in the combination, arrangement and details of construction disclosed in the drawings and specification, and then more particularly pointed out in the appended claims.

In the drawings, wherein similar reference characters designate similar parts throughout the respective views;

Figure 1 is a plan view of a paper blank out of which my invention is to be foldably produced,

Figure 2 is a sectional end elevation thereof,

Figure 3 is a cross section taken on line 3—3 of Figure 2,

Figure 4 is a perspective view of my invention with the package opened to permit accessibility of the hair pins nested therein.

In the drawings, which are merely illustrative

2

of my invention, all details are made to appear:

The invention is produced from an oblong-shaped paper blank broadly designated 10. The opposite long edges thereof are designated 11, 12, while the end edges, which are at right angles to the side edges 11, 12, are designated 13 and 14.

The rectangular paper blank 10 is provided with five transversely extending score lines, respectively designated 15, 16, 18, 23 and 26. The score line 26 is located contiguous to the end edge 14 of the blank. Score line 15 and score line 18 set apart a slightly longer panel B than the panels A, C, and D, formed by the other score lines.

15 The panels C and D, being two outermost of the entire series of panels, are wider than the other panels A and B, because each panel is formed with marginal portions forming the oppositely arranged rectangular wings 19, 20 for panel

20 C, and 24, 25 for panel D. Wings 19, 24, and wings 20, 25, form practically each in turn, a single marginal strip which juts out from each long edge 11, 12, of the paper blank 10. The opposite ends of one strip are denoted at 21, 21a, and those of the other strip are denoted at 22, 22a. It will also be seen slits 28, and 29, divide these strips centrally, which slits are straight line continuations of the score line 23.

15 The panels C and D, being two outermost of the entire series of panels, are wider than the other panels A and B, because each panel is formed with marginal portions forming the oppositely arranged rectangular wings 19, 20 for panel

20 C, and 24, 25 for panel D. Wings 19, 24, and wings 20, 25, form practically each in turn, a single marginal strip which juts out from each long edge 11, 12, of the paper blank 10. The opposite ends of one strip are denoted at 21, 21a, and those of the other strip are denoted at 22, 22a. It will also be seen slits 28, and 29, divide these strips centrally, which slits are straight line continuations of the score line 23.

Panel D, one of the endmost of the series of 30 panels, is formed with a flap extension 27, which is a rectangular portion projecting beyond the score line 26. This flap is of the same transverse extent as the panel D upon which it is formed.

The package is formed from the blank herein- 35 before described as follows: Panel D is folded back upon the panel C so that the bight portion 23a thereof is formed by the fold or score line 23 upon which these panels are folded. Panel B is then folded upon score line 18, back upon panel

40 C in such a manner that panel B may foldably overlap panel C and so that its bight portion 18a is remotely opposite to bight portion 23a of panels C and D.

Panel A is folded upon score line 15, and panel 45 B is folded upon score line 16, so that the intervening strip 17 between score lines 15 and 16 serves the purpose of a hinge upon which panel A may be bent back over upon and in overlapping relation against the remaining body of the package.

In this disposition of the folded parts of the paper blank 10, as illustrated in Figure 4, it will be seen that the bight portion 23a of panels C and D is located at the outer end of panel B so that a portion 25 of panel B extends slightly beyond this

bight portion 23a. This is done because it is proposed to enlarge the transverse area of the hair pin supporting part of the package contributed by panels C and D and the wings 19, 20, 24, 25 and flap 27 thereof. The cover of the package is the panel A thereof. Because of the fact that portion 35 extends slightly beyond bight portion 23a, this cover is able to bend around the widened area of the hair pin supporting stand formed conjunctively by folded panels C and D.

The wings 19, and 24, on one marginal portion of the folded back panels C and D, and the wings 20, 25, on the opposite marginal portion thereof, are folded back respectively upon longitudinally extending score lines 19a, 24a, and 20a, 25a respectively, as shown in Figure 4, to provide the longitudinally extending bight portions 25b, 20b, for each pair of wings on either margin of the stand.

In order to hold the opposing wings 20, 25, and 19, 24 in a disposition so they diverge inwardly over the opposing marginal portions of the stand made conjointly by folded panels C and D and face the center of the strand, I bend back flap 27 on panel D.

The flap 27 is folded back upon score line 26 so its bight portion 26a is opposite to and flush with bight portion 18a made by panels B and C foldably. A staple 32 is pressed in to flap 27 and panels D and C and the panel B which forms a backing for the package. The opposing ends 33, 34 of this flap overlap the outer parts of wings 24 and 25 and serve thereby to confine these wings between panel D and flap 27. The flap 27 thus extends across the width at the lowermost part of the completed package.

In the completed package thus made, panel B serves as a backing, panel A as a cover, while the opposite pairs of wings serve as fluted guards located at the longitudinal margins of the package. The flap 27 serves to close the lower part of the package, and cover panel A serves to close the upper part of the package, and the fluted wings cover the opposing margins thereof. This completely encloses a row of bobby pins or hair pins E which are nested suspendingly in abutting relation in a manner to be sandwiched effectively between the panels A and B when the package is closed. It will be seen that the bobby pins have their bight portions strung over the bight portion 23a of the stand made by folded panels C and D, and that their long stems straddle the length of the respective panels C and D. The lower ends of these bobby pins or hair pins extend slightly into the fold produced by and between flap 27 and the adjacent part of panel D. In this manner the hair pins as a single row are engaged only at their ends for holding purposes.

When the cover panel A is unfolded as shown in Figure 4, instant accessibility is given to any of the hair pins nested upon the stand. The fluted wings or guards at the longitudinal margins of the stand will confine both stems of all hair pins that enter the same should the package be held so that they may enter or slide into these fluted guards. The guards prevent the hairpins from becoming separated from the package by way of the marginal edges of the package, whether the cover be in open or closed position. The backing panel B and cover A when the package is closed, and the backing panel B and flap 27, when the package is open, both prevent sidewise displacement of the hair pins from nested relation upon the bight portion 23a of the stand. The hinge strip 17 virtually holds the hair

pins against endwise displacement from the package in one direction, while the bight portion 26a holds them against endwise displacement from the package in a counter direction.

5 I do not mean to confine myself to the exact details herein disclosed save as pointed out in the appended claims.

What I claim is:

1. An oblong paper blank folded upon itself to provide four successive panels, the two outermost panels being folded one upon the other so hair pins may be suspended upon their bight portion, with one of these panels folded back over another panel to provide a backing for one side of the row of hair pins, and the remaining end panel serving as a cover to overlie the other side of the row of hair pins so that its bight portion holds the pins against endwise displacement in one direction, marginal portions folded back upon the first named panels to serve as guards for confining the hair pins against marginal displacement, and means connecting both of the guards for confining the outer ends of the hair pins.

2. As a new article of manufacture, a paper blank having portions thereof folded back upon itself to provide four successive panels, the two outermost panels having marginal wings separated endwise, so these panels fold, one upon the other, and so that the wings fold back marginally upon their panels and extend opposite the marginal portions of the latter to provide guards, a row of hair pins having the bight portions strung upon the bight portion of these panels so as to be enclosed by said guards, a third folded panel forming a backing for one side of the row of pins, the fourth folded panel forming a cover for the other side of the pins so that the hair pins are enclosed between cover and backing.

40 3. As a new article of manufacture, a paper blank having four successive panels, the two outermost of the panels being folded, one upon the other, the other two panels being folded, also one upon the other, so that one bight portion may be disposed between the other panels in their folded relationship, marginal wings formed upon the last named panels, folded back so as to overlie the marginal edges of these panels and together on each margin thereof providing 45 margin enclosing guards, and a flap carried by 50 one of the first named panels being cleated onto one of the last named panels so as to extend across and terminally overlie said guards.

4. A device as described, consisting of a paper package having a pair of folded panels upon the bight portion of which hair pins are adapted to be nested straddlingly, oppositely arranged wings formed marginally upon both panels, bent back over the marginal portions of these panels to confine the hair pins against marginal displacement from the panels, means holding the hair pins against displacement from the panels at one end of the package, and means holding them against displacement therefrom at the other end of the package.
